FOOT OPERATED HYDRAULIC PUMP

George W. McLellan, Bartlesville, Okla.

Application June 5, 1950, Serial No. 166,232

2 Claims. (Cl. 103—41)

1

My invention consists in new and useful improvements in a foot operated hydraulic lifting jack of the type primarily designed for use in connection with automotive vehicles and has for its object to provide a device of this character which possesses all of the advantages inherent in hydraulic jacks, yet at the same time is so constructed as to be collapsible for purposes of storage when not in use.

A further object of my invention resides in the provision of a novel collapsible foot operated pump rod and supporting frame or extension which, when extended facilitates the positioning of the jack and enables the operation thereof at a relatively distant point without inconvenience and soiling of the clothes and hands of the operator which usually attends such an operation.

Another object of my invention is to provide an extendable and collapsible frame pivotally connected to the base of the jack adjacent the circulating pump and so arranged as to slidably support both a collapsible pump rod and a collapsible relief valve actuating stem whereby when in extended position, the entire operation of the jack may be accomplished at a point remote from the jack itself.

A still further object of the invention is to provide an assembly of this character which may be manufactured at a relatively low cost, is easily operated and is readily adaptable for various lifting purposes.

With the above and other objects in view which will appear as the description proceeds, my invention consists in the novel features herein set forth, illustrated in the accompanying drawing and more particularly pointed out in the appended claims.

Referring to the drawing in which numerals of like character designate similar parts throughout the several views:

Figure 1 is a top plan view of the jack assembly;

Figure 2 is a longitudinal sectional view taken on line 2—2 of Figure 1;

Figure 3 is an enlarged sectional view taken on line 3—3 of Figure 1, showing the relief valve structure; and

Figure 4 is a view in side elevation, showing the jack assembly in folded or collapsed position.

In the drawing, 5 represents the main base of the jack which may be composed of any suitable metal, cast to form a centrally disposed raised portion or annular body 6, recessed as at 7 to form the base of a fluid reservoir as will be seen

from Figure 2. Adjacent its upper extremity, the inner wall of the recess 7 is threaded to receive complementary threads of a reservoir housing 8, the upper portion of which is preferably frusto-conical and provided in its top wall with a concentric opening in sealed engagement with a central cylinder 9, the lower end of which is in threaded engagement as at 10, with a raised seat, concentric with the reservoir base in the body 6. Suitable sealing rings 11, 12 and 13 may be provided between the upper end of housing 8 and the cylinder 9, between the lower end of the cylinder 9 and its supporting seat, and between the lower end of the housing 8 and the body 6, respectively.

Within the cylinder 9, I provide a pair of telescoping jack sleeves, namely an outer sleeve 14 and an inner sleeve 15, the latter being closed at its upper end which supports a jack head 16, preferably by means of a threaded connection, suitable sealing rings 17 being provided between the cylinder 9 and the outer sleeve 14 and between the outer sleeve 14 and the inner sleeve 15, all as shown in Figure 2. The upper face of the head 16 is preferably provided with a series of raised studs 18 to facilitate its firm engagement beneath a motor vehicle axle or other objects to be lifted.

The central portion of the body 6 immediately beneath the cylinder 9 and the telescopic jack sleeves 14 and 15, is recessed to provide a pressure well 19 which is slightly enlarged at its upper portion to provide an annular shoulder 20 for limiting the descent of the jack sleeves, the interior of the inner sleeve 15 being in open communication with the well 19.

One side of the body 6 is extended longitudinally of the base as at 21, to accommodate the circulating pump and relief valve, said pump consisting of a cylinder 22 formed in the extension 21 and within which a horizontal pump piston 23 is adapted to reciprocate. The stem 24 of the piston 23 projects from the cylinder 22, through a gland 25, where its bifurcated outer extremity is pivotally connected as at 26, to the adjacent end of a collapsible piston rod 27 which is slidably supported in a collapsible frame or base extension, generally indicated by the numeral 28.

The frame 28 preferably consists of a plurality of substantially trough-like sections, longitudinally joined for relatively hinged movement. The innermost section 29 is pivotally connected as at 30 to the upper face of the base 5 and the next section 31, is longitudinally spaced 55 from the adjoining section and is hinged con-

nected thereto by means of a U-shaped coupling 32 which overlies the adjacent ends of said sections and is pivoted to their respective ends as at 33. At the outer end of the frame or extension 28, I provide a foot pedal 34 which is pivotally mounted on the frame as at 35, and extends inwardly over the frame, the underside of said foot pedal being operatively connected to the free end of the pump rod 27 by means of a link 36 pivoted to the foot lever at 37 and to the pump rod at 38.

The pump rod 27 is similarly composed of a plurality of longitudinally jointed sections, the innermost of which 39, is pivoted to the piston stem at 26 as previously described, the next section 40, being longitudinally spaced from the former and hinged thereto by a U-shaped coupling 41 which is connected to the respective rod sections by transverse pivots 42. In order to slidably support the piston rod 27 for reciprocating movement in the frame 28 and at the same time prevent its lateral displacement, I preferably provide a transverse web 43 which extends across one end of the innermost section 29 of the frame, said web being so positioned with respect to the coupling 41 as not to interfere with its reciprocation.

At the operating end of the piston rod 27 the section 40 thereof is provided with a coil spring 44, the inner end of which abuts a fixed ring 45 in the frame, with its outer end in engagement with a collar 46 secured to the rod section. Thus upon depressing the foot pedal 34 the rod 27 and the piston 23 are forced inwardly and upon releasing the foot pressure the piston, piston rod and foot pedal are returned to normal position by spring 44.

Returning to the body 6 supporting the reservoir, it will be noted that said body is provided with a passageway 47, placing the inner end of the cylinder 22 in communication with the pressure well 19 beneath the jack sleeves, a check valve 48 being located within the passage and arranged to permit the injection of fluid from the cylinder into the pressure well 19 but to prevent its ejection therefrom. A branch passage 49 connects the passage 47 with the lower extremity of the reservoir and this passage is similarly provided with a check valve 50 which acts in the opposite direction, that is, the valve 50, is arranged to permit the withdrawal of fluid from the reservoir but to prevent the entrance of fluid therein from the passageway 47.

The operation of the mechanism thus far described is as follows. Upon manipulating the foot pedal 34, the piston rod 27 is reciprocated in the frame 28, which in turn causes the reciprocation of the piston 23 in the cylinder 22. On each return stroke of the piston 23, under the action of spring 44, fluid is withdrawn from the reservoir 8 past valve 50, into the cylinder, and is injected into the pressure well 19 through valve 48, when the piston is again advanced by the action of the foot pedal 34, so that repeated operation of the foot pedal causes the fluid pressure to build up within the well 19 and the jack sleeves 14 and 15, to elevate the jack head to the desired extent.

The release of the fluid pressure from the jack sleeves and the well 19 for permitting the jack to descend, is effected by means of a relief valve located in the body extension 21 and shown in detail in Figure 3. Here it will be seen that a needle valve 51 carried on a valve stem 52, is reciprocably mounted in an opening in the body

6 and acts to normally close a restricted passageway 53 which leads into the pressure well 19. Preferably, a ring 51' of synthetic rubber or other suitable material is fitted on the needle valve to engage and close the restricted passageway 53 when the valve is thrust inwardly as in Figure 3. A branch passageway 54 connects the passageway 53 with the interior of the reservoir and thus, when the valve 51 is withdrawn, fluid from the well 19 is permitted to flow back through the passageways 53 and 54, and return to the reservoir.

The operating connection for the needle valve 51 is similar to that for operating piston 23 and as will be seen in Figure 1, the valve stem 52 is hinged to the first section 55 of the valve stem extension, by a U-shaped coupling 56. A second section 57 of the valve stem is similarly hinged to the opposite end of section 55 by a U-shaped coupling 58. The sectional valve stem is also slidably and rotatably supported in the frame 28 by means of the cross web 43 and the outer extremity of the frame is preferably provided with a bracket 59 for slidably supporting the protruding end of section 57 of the valve stem, which is provided with a handle 60.

A coil spring 61 is interposed between the handle 60 and the outer face of the bracket 59 and normally tends to retract the valve stem to open the relief valve 51. However, the valve may be locked in either open or closed positions by means of a radially projecting pin 62 fixed to the stem section 57 and arranged to cooperate with a slot (not shown) in the inner face of the bracket 59. By simply turning the handle 60 to the right or left and pushing the stem inwardly, the pin 62 passes through the slotted bracket 59 to close the valve, said valve being locked in this position by a turn of the handle 60 to bring the pin 62 into engagement with the inner face of the bracket, as shown in Figure 1.

To open the valve 51, the handle is rotated to release the pin 62 which again passes through the slotted bracket under the action of the spring 61 until the pin engages the outer wall of the bracket 59 which limits the outward movement of the valve stem. In this position the valve 51 permits the return of the fluid from the well 19 to the reservoir through passages 53 and 54. It may be noted that this is the normal inoperative position of the valve stem which brings the joint 58 to rest adjacent the piston rod joint 41. Thus, when the assembly is to be folded, the handle 60 must be rotated to bring the pivots of the joint 58 into proper transverse alignment with the respective pivots of the rod joint 41 and the frame joint 32.

My improved arrangement of jointed piston rod, valve stem and supporting frame, affords a convenient means of inserting the jack assembly in positions of difficult accessibility by using the frame as a means of locating the jack. Furthermore, the jack may be operated at a considerable distance from the point of elevation and when not in use the entire assembly may be conveniently collapsed for storage. As shown in Figure 4, the outer section 31 of the frame is folded on to the inner section 29 by means of the joint 32 and the inner section 29 is folded upwardly on the hinges 30, the sectional piston rod and valve stem being simultaneously folded by means of their respective hinge connections. As before indicated, the hinged couplings of the piston rod and the valve stem are so located and adjusted with respect to each other and to the

couplings of the supporting frame, that when in normal positions, the pivots of the joints are in transverse alignment and the entire collapsible assembly can be folded without difficulty.

From the foregoing it is believed that my invention may be readily understood by those skilled in the art without further description, it being borne in mind that numerous changes may be made in the details of structure without departing from the spirit of the invention as set forth in the following claims.

I claim:

1. In a pump including a base, a horizontal pump cylinder mounted in fixed relation on said base, a piston operating in said cylinder; a piston-actuator assembly comprising an elongated collapsible, ground-engaging frame, pivotally mounted at one end on said base and adapted to be swung to a horizontal ground-engaging position adjacent said base, said frame being formed of a series of sections of substantially U-shaped cross section, hingedly connected in end-to-end relation, a collapsible piston rod of a length substantially equal to that of said frame, pivotally connected at one end to said piston, longitudinally spaced cross members in said frame supporting said rod for longitudinal reciprocation in the frame when the latter is in extended position, said piston rod being formed of a series of sections hingedly connected in end-to-end relation, at points normally lying adjacent corresponding hinge connections of said frame, and a foot pedal pivoted on the outer end of said frame and op-

eratively connected to the adjacent end of said rod, said frame and piston rod being simultaneously extendable from said base to a horizontal operating position.

2. A device as claimed in claim 1 including a release valve in said base, communicating with said cylinder and a collapsible valve-actuating stem pivotally connected thereto and formed of a series of sections hingedly connected in end-to-end relation, at points normally lying adjacent corresponding hinge connections of said frame and piston rod, said valve-actuating stem being slidably supported in said frame and simultaneously extendable from said base, with said frame and piston rod.

GEORGE W. McLELLAN.
